Primary Examiner — Catherine S Posthauer*Assistant Examiner* — Amina Rahman*(74) Attorney, Agent, or Firm* — Nitin Kaushik(57) **CLAIM**

The ornamental design for a seat belt buckle, as shown and described.

DESCRIPTION

FIG. 1 is a top, rear and right side perspective view of a seat belt buckle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing the seat belt buckle in an alternative folded position.

The broken lines are shown for the purpose of illustrating exemplary environmental subject matter and form no part of the claimed design.
